MECHANICAL POOL TABLE

Julian H. Thomas, Rocky Mount, N. C.

Application October 11, 1932. Serial No. 637,305

8 Claims. (Cl. 273—11)

This invention relates to certain improvements in the construction of mechanical pool tables in which unauthorized use of the table is prevented by trapping the balls and preventing them from being put back on the table. Such mechanical pool tables have gone into extensive use in public amusement places. By the installation of the mechanical features for controlling the use of the tables it is possible to control play upon the tables to that which is strictly accounted for to the proprietor. In the absence of such mechanical features it is necessary to have an attendant to supervise the play and to see that proper payment is made by the players. On the other hand, where a mechanical control is placed upon the tables not only is it possible to dispense with the attendant but it also assists in accounting for the payments required of the players for the use of the table and eliminates the necessity of keeping any separate accounts. There is the ever present temptation for players to make unauthorized or unpaying use of the tables unless such mechanical features are protected against harm or tampering. I have devised in this invention an arrangement of structural details which may be quickly installed or added to the conventional pool tables. Such additional features do not mar the appearance of the tables nor their usefulness. It is one of the objects of my invention to provide a mechanical control over the supply of playing balls and to have this control unobtrusive but effective to prevent unauthorized use of the table.

Other advantages of my invention will be readily observed from the following description of the preferred form of my device as illustrated in the accompanying drawing.

In the drawing

Fig. 1 is a plan view of the table with the top removed;

Fig. 2 is a longitudinal vertical section on the line 2—2 of Fig. 1;

Fig. 3 is a transverse vertical section on the line 3—3 of Fig. 1;

Fig. 4 is an enlarged vertical section taken on the line 4—4 of Fig. 1;

Fig. 5 is a similar section showing the parts in different positions;

Fig. 6 is a representation of a playing ball and

Fig. 7 is a representation of the cue ball.

For the purposes of illustrating my invention without limitation thereon, I have shown in the accompanying drawing an arrangement by which the balls after dropping in the pockets of the pool table are collected by being caused to roll by gravity to a common point. At this point the balls are sorted according to size so that the cue ball which is conventionally of slightly greater diameter than the other balls, will be diverted for free delivery outside of the table. At the same time the remaining balls of the set will drop down

to a receiver. At this point the balls are either brought to rest on one wall of the receiver or may more probably fall within the trough of the receiver. The receiver is designed to discharge by tilting but this tilting movement is under the control of the customary check-controlled devices. In this way while the balls are always free to drop into the receiver, their delivery outside of the table or their return to the players, is dependent upon the actuation of the check-controlled device. Suitable arrangements of the devices are provided to insure retention of the balls until the completion of the release of the check-controlled device.

The customary table 8 is of the usual massive construction and surmounted by the slate top, not illustrated. The table has a series of channels 9 extending from beneath each of the several pockets in the top. These channels converge to a common point 10 at a lower level. At this point the channels deliver to a sorting plate 11. This plate is slotted as shown at 12 so that the larger size cue ball 13 will roll along the sorting plate 11 while the smaller balls of the set 14 will drop readily through the slot 12.

Extending from beneath the sorting plate 11 longitudinally of the table is an inclined delivery chute 15 having its end 16 beyond one end of the table. This chute 15 receives the cue ball 13 and delivers it without further obstacle at the end of the chute 16.

The other balls which fall through the slot 12 travel down an inclined chute 17 and off the end thereof.

Running from side to side of the table is placed an abutment or baffle 18 as a rest against which the balls remain until they fall in the trough of the receiver and the length of the abutment 18 is sufficient to hold the full set of balls.

Immediately beneath the free end of the chute 17 and likewise extending from side to side of the table is a receiver 19. This receiver is in the form of a trough having its side walls 20, 20. The ends of the trough are mounted on pivot pins or screws 21 which in turn are supported from the inner side walls of the table. The trough 19 will ordinarily be right side up and the playing balls delivered from the chute 17 will drop into this trough after striking the abutment 18. The length of the trough is such as to accommodate the full set of balls being used in any game.

Under some circumstances the trough may have been left inverted as is shown in Fig. 5. In this case the balls remain in the V-shaped pocket formed by the abutment 18 and upper side wall 20 of the trough until such time as the trough is tilted back to its normal position.

The tilting of the trough is accomplished by means of an operating rod 22 which is pivoted by means of an eyelet or other device 23 to one

side wall 20 of the trough. The opposite end of the rod 22 is connected to the inner end of a plunger 24 which forms the movable part of a check-controlled device 25. This device 25 is mounted on the end panel 26 of the table. Since these check-controlled devices are well known it is deemed unnecessary to describe them in detail. In general they consist of the plunger 24 movable in and out of the device 25. A coin or other check is advanced by the plunger 24 through the device 25 and releases the plunger for its full inward movement at the conclusion of which the coin or check is dropped into a locked drawer 27. The device 25 is of such nature as to prevent the full movement of the plunger inward except when the coin is used and also to prevent a return movement of the plunger 24 before the inward movement is completed.

With the plunger 24 operating as described the movement of the trough will be apparent. Assuming the balls of the set have been played at the conclusion of one game, they will have dropped into the pockets of the top and travel by gravity into the upturned trough 19. The inward movement of the plunger 24 is obstructed by the device 25 until released by the use of the appropriate coin. Since the plunger 24 is pushed to its innermost position, the trough 19 tilts to a limit discharge position. Stopping the plunger 24 before the completion of the movement allows the balls to take the position shown in Fig. 4 in which they are at rest between the edge of abutment 18 and the top of the side wall 20. The discharge of the balls will not take place but the balls form a substantial lock of the device and the use of the balls for playing is impossible until the movement of the plunger is completed. In the final phase of this movement the balls are released from between abutment 18 and the wall 20 and fall into the delivery tray 28. The balls may then be obtained by the players and set up again on the top of the table.

In the event that an attempt is made to obtain a set of balls without restoring the plunger 24 to its outer position and using another coin for releasing, a condition occurs such as is illustrated in Fig. 5. In this case the trough 19 having been left in an inverted position serves to block the fall of the balls until the trough is again brought right-side-up.

A locked panel 29 is provided to close the bottom of the table beneath the trough 17. In this way, it may be unlocked for access to the mechanism or for cleaning purposes but otherwise the bottom of the table is inaccessible to the players.

In like manner a permanent panel 30 is provided to close off the remaining bottom portion of the table.

From the above description it will be readily apparent that I have provided an efficient and simple arrangement for trapping the balls that have been played and holding them until such time as they are again delivered to the players in exchange for the requisite coin or check. The installation of this equipment to the ordinary pool table is easily accomplished without altering the general appearance of the table. The device serves as an efficient protection against the unauthorized use of the table and is of material economy in the maintenance and supervision of commercial installations.

While I have illustrated the preferred form, still it is to be borne in mind that this is merely for the purpose of example and without limiting

the scope of the invention beyond the terms of the following claims.

What I claim is:—

1. A pocket pool table, channels connecting the pockets of said table by gravity to a common point, a tilttable walled trough extending transversely of the line of travel of the balls and to which the balls are conveyed, from said common point, delivery means for said balls and operating means for emptying the trough into the said delivery means, said operating means being normally inoperative. 80

2. A pocket pool table, channels connecting the pockets of said table by gravity to a common point, a tilttable walled trough extending transversely of the line of travel of the balls and to which the balls are conveyed, from said common point, delivery means for said balls and check-controlled means for emptying the trough into the said delivery means. 90

3. A pocket pool table, channels connecting the pockets of said table by gravity to a common point, a tilttable walled trough extending transversely of the line of travel of the balls and to which the balls are conveyed, from said common point, delivery means for said balls, means for holding the trough against movement and check-controlled means for releasing the trough to discharge the balls into the said delivery means. 95

4. A pocket pool table, channels connecting the pockets of said table by gravity to a common point, an invertible walled receiver to which the balls are conveyed, from said common point, delivery means for said balls, means for controlling the inversion of the receiver to discharge the balls into the said delivery means. 105

5. A pocket pool table, channels connecting the pockets of said table by gravity to a common point, an invertible walled trough extending transversely of the table and to which the balls are conveyed, from said common point, delivery means for said balls, means for inverting the trough, and check-controlled means for operating the inverting means. 115

6. A pocket pool table, channels connecting the pockets of said table by gravity to a common point, an invertible trough extending transversely of the table and to which the balls are conveyed, from said common point, an abutment cooperating with the trough to hold the balls, 125 delivery means for said balls, and means for tilting the trough to separate it from the abutment to discharge the balls into the delivery means.

7. A pocket pool table, channels connecting the pockets of said table by gravity to a common point, a walled trough pivoted at its ends to the opposite sides of the table and receiving the balls, from said common point and deflecting them at right angles from their line of travel, a delivery tray beneath the trough and accessible from 135 outside the table, and check-controlled means for controlling the discharge of balls from the trough to the tray.

8. A pocket pool table, sloping channels connecting the peripheral pockets thereof to a common point beneath the level of the table, a trough pivoted at its ends to the opposite sides of the table, a delivery tray for said balls, an abutment parallel to said trough, means to cause the balls to roll from said common point and be collected 145 in the space between the abutment and the trough and means to successively transfer the balls into the trough and thence into the delivery tray. 140
